MINIATURE PHONOGRAPH

John H. Wilhelm, Hamilton Beach, Long Island,
N. Y., assignor, by mesne assignments, to
Voices, Incorporated, Newark, N. J., a corpora-
tion of Delaware

Application August 15, 1933, Serial No. 685,217

15 Claims. (Cl. 274—17)

This invention relates to phonographs, and more particularly to miniature phonographs adapted for use in dolls or other toys.

The primary object of the present invention is to generally improve miniature or toy phonographs, particularly phonographs intended to be embodied in dolls. More particularized objects of the invention are to provide a phonograph which will reproduce a relatively long record 10 with ample loudness and clarity, while at the same time confining the phonograph to compact dimensions making the same usable in dolls of small or moderate size. An ancillary object of the invention is the provision of a relatively long 15 horn of continuous expansion in cross-section, which improves the sound quality of the phonograph and yet which is so disposed in the phonograph that it does not appreciably increase its bulk or size.

Further objects of my invention are to make necessary only a single opening in the phonograph, and consequently in the doll, for sound discharge from the phonograph and for affording ready change of the record being played; to use a record supporting and rotating drum as a part of the horn or sound amplifying system; to localize all of the necessary controls of the phonograph at one side thereof, specifically at the sound discharge side of the phonograph; to include among such controls not only means for winding the phonograph but also means for disengaging the stylus from the record, means for restoring the stylus to initial position, and means for braking the governor and thereby stopping the phonograph; and to combine all of these controls except the winding key of the phonograph into a single control element for automatically and in proper sequence disengaging the stylus, moving the same to initial position, and 40 braking the governor. An additional object of the invention resides in the provision of a sound box so mounted as to be oscillatable about its center for movement of the stylus on the record and about an axis extending thereacross for movement of the stylus toward and from the record, the sound box being for this purpose oscillatably mounted on a sound box supporting horn extending across the sound box and itself oscillatably mounted in the phonograph frame. 45 Other objects are to so design the phonograph that it may be made inexpensively, as, for example, by the use of simple spur gearing between the main spring and the record carrying drum.

To the accomplishment of the foregoing and

such other objects as will hereinafter appear, my invention consists in the miniature phonograph elements and their relation one to the other as hereinafter are more particularly described in the specification and sought to be defined in the 5 claims. The specification is accompanied by drawings in which:

Fig. 1 is a section in elevation through a phonograph embodying features of my invention;

Fig. 2 is a transverse section taken in the plane 10 of the line 2—2 of Fig. 1;

Fig. 3 is a rear elevation of the phonograph with the gear cover removed; and

Fig. 4 is a section taken in the plane of the line 4—4 in Fig. 2.

Referring to the drawings, the phonograph comprises a hollow open-ended record supporting drum D carrying a cylindrical record R, the drum D being driven through gear train T by a main spring S. The sound impression of the record is translated by a sound box B carrying a stylus or needle N. Sound box B is oscillatably mounted on a sound box supporting horn H, thus affording movement of needle N along the record, and the horn H is itself oscillatably mounted in 25 the frame of the phonograph, thereby affording movement of the needle N toward and away from the record R. The sound box supporting horn H is only a first horn section, it communicating at its large end with the small end of a second 30 horn section, this taking the form of a channel C extending along the back of the phonograph frame to the rear end of the drum D. The latter serves as a third or final horn section, and sound flowing therethrough is discharged from the 35 phonograph at a single main opening O which thus acts not only as a sound discharge opening but also to permit ready removal and replacement of the record R on drum D.

The control of the phonograph is localized on 40 the same side of the phonograph as the sound discharge opening O and is embodied in a winding key K and a single control means M, the latter being arranged to disengage the needle N from the record by oscillating the sound box supporting horn H, to move the needle back to its starting position by oscillating the sound box B, and to stop the phonograph by braking the phonograph governor G. The bending of the sound amplifying horn in the manner shown, and particularly the utilization of the drum D as the large 45 end of the horn, results in an exceedingly compact phonograph structure, the phonograph being little if at all larger than it would be without the provision of the horn. The phonograph may be 50 55

inserted in the body of a doll with the front wall of the phonograph at the back of the doll, thereby providing for sound discharge from the doll, for record changing as well as for winding and controlling the operation of the phonograph all within a confined area at the back of the doll.

Considering the phonograph structure in greater detail, the frame comprises a front plate 12 and a back plate 14 connected by spacers 16. For the sake of lightness these spacers are preferably made of sheet metal bent into channel form, and are secured to the front and back plates 12 and 14 by tongue and slot construction.

The record drum D is driven by main spring 15 S through the gear train T. The spring is preferably a wide ribbon spring housed within an appropriate spring housing 20, the inner end of the spring being secured to a winding stem 22, as is best shown in Fig. 2, and the outer end of the spring being secured to the housing 20. For this purpose the spring may be perforated and anchored on one or more lugs or hooks 24 struck inwardly from the periphery of the spring housing.

The spring housing 20 is formed integrally with a housing shaft 26 the inner part 28 of which is preferably enlarged and counter-bored to rotatably receive the inner end 30 of winding stem 22. The outer end of the winding stem is squared and has fitted thereon the winding key K. The winding stem is provided with a ratchet to prevent unwinding of the spring at the key, and for this purpose I prefer to use a simple coiled spring 32 wound about the winding stem and having one end 34 anchored in front plate 12 of the frame. The housing shaft 26 carries at its outer or rear extremity a gear 36 which meshes with a pinion 38 fixed to an intermediate gear 40 and which in turn meshes with a pinion 42 mounted on the drum shaft 44.

The drum D is hollow and open-ended, the front end of the drum being entirely open, and the rear end of the drum consisting solely of spider arms 46 connecting the drum to a hub 48 which is fixed on the drum shaft 44. The outer diameter of the drum is dimensioned to receive the cylindrical record R with a smooth snug fit. To insure rotation of the record without a tight force fit therebetween, the outer wall of the drum is preferably provided with a plurality, say four, spaced thin rails or ribs 50 which may taper slightly toward the front end of the drum.

The record R is cylindrical in shape and may, if desired, be fitted with a transverse rod 51 at its outer end, this rod facilitating removal of the record from the drum through the opening O, and also serving to prevent the record from being placed on the drum with the wrong end foremost.

The sound box B is generally circular in outline and comprises a dished sheet metal casing 52 carrying an appropriate diaphragm 54. The edges of the diaphragm are preferably supported between resilient annular spacers 56. The sound box enclosure is completed by a top plate 58, the edges of casing 52 being rolled or folded over the edges of top plate 58. The stylus or needle N preferably consists of a small sapphire 60 mounted at one end of a pivoted stylus arm 62, the opposite end of the stylus arm passing through a slot 64 in the sound box casing 52 and being attached to the center of the diaphragm. To pivot the arm 62 on the sound box in a frictionless manner, the arm is secured to a cross plate 66 which itself carries fulcrum points 68 resting in mating indentations on the side wall of sound box casing

52. The fulcrum points 68 and the arm 62 are held in place by a spring 70 the inner end of which is clamped within the periphery of the sound box, and the outer end of which is bifurcated to straddle the arm 62 and bears against the cross plate 66, this being most clearly shown in Fig. 1. It will thus be evident that vibrations imparted to the stylus by hill and dale sound grooves are transmitted to the diaphragm 54 and are there translated into sound waves. It should be understood that while I have disclosed a stylus and lever arrangement adapted for hill and dale recording, the sound box may, if desired, be readily modified to adapt the same for lateral sound recording.

The top plate 58 of the sound box is provided with an annular flange 72 defining a sound discharge opening within which there is centrally disposed a small hub 74 supported by spokes or arms 76. These parts mate with corresponding parts on the sound box supporting horn H. The latter is generally rectangular in cross-section, as is best shown in Fig. 2, and includes a small end closed by a wall 78, and an outwardly flared large end 80 which bears slidably against the inner wall of frame plate 14 and discharges through an opening 82 in said frame plate. The support member H is continued in the form of an open channel to an opposite end 84 adjacent the front frame plate 12. It will thus be seen that the member H extends across the sound box between frame plates 12 and 14. It is oscillatably mounted in the frame, this mounting being exemplified in the present case by pins 86. The bottom wall of the member H is provided with a flange or seat 88 which receives the flange 72 of the sound box and forms therewith a sound flow channel from the sound box into the horn. The member H is further provided with a hub 90 supported by spokes or arms 92. A bearing pin 94 is secured at its inner end to the sound box and passes through hub 90 and through the outer wall of member H to an appropriate means 96 for oscillating the sound box. It may be pointed out that the fit between the flanges 72 and 88 is preferably made quite loose and free so that the oscillation of the sound box will be substantially frictionless. The load and oscillation of the sound box is preferably taken by a slender bearing such as the pin 94, as this offers little resistance to oscillation and consequently no interference with movement of the stylus along the record as the stylus tracks in the sound groove.

The assembly is urged clockwise, as viewed in Fig. 2, by a spring 98 tensioned between the upper portion of the horn and the frame, thereby urging the stylus into engagement with the sound record regardless of the position of the phonograph. The resulting movement is limited to permit the stylus to move inwardly further than the periphery of the record and yet to avoid contact of the stylus with the drum when no record is placed on the drum. In the present case the stop means consists simply of the upper wall 100 of the spacer or channel member 16 shown adjacent the horn H in Fig. 2.

The complete horn of the phonograph is generally U-shaped, and the second or middle section of the horn extends along the back plate 14 of the phonograph. For this purpose the back plate is depressed or channeled, as is shown at 102 in Fig. 1, and an additional dished or channel-shaped member 104 is added to the frame plate 14. This member 104 remains constant in depth but expands in width, as is best shown in Fig. 3, thus providing for continuing expansion of the horn 75

from the entrant end 102 opposite the sound box supporting horn H to the discharge end 108 which is opposite the rear end of the drum D. The frame plate 14 is, of course, open or cut away to form a large hole in alignment with the drum D, and some of the material is preferably bent inwardly to form the flange 110, best shown in Fig. 1, which leads directly to the drum. A single bar or strap of sheet metal 112 may be left intact on the frame plate and acts as a support for the drum shaft 44.

The drum D is itself of varying thickness, it being substantially thicker at the rear or sound entrant end 114 than at the front or sound discharge end 116. Furthermore, the record R, projecting forwardly from the drum, is of larger internal diameter than the drum. The front frame plate 12 is cut away to form the sound discharge opening O, and the material of the plate is preferably bent inwardly to form a flange 118 which is of still larger diameter. This affords continued expansion.

The speed of the phonograph is controlled by governor mechanism G. To drive the governor, the drum D is provided at its rear periphery with a worm gear 120 which meshes with a worm 122 on the governor shaft 124. The governor shaft is borne between conical bearings 126 mounted on lugs 128 bent upwardly from the rear frame member. The governor may be of conventional type, and in the present case comprises leaf springs 130 carrying weights 131 and secured at the end 132 to the governor shaft and at the other end 134 to a sleeve 136 slideable on the governor shaft and carrying a brake disc 138. Brake disc 138 cooperates with a fixed brake shoe 140 the position of which may, if desired, be adjustable, but which in any case determines the normal operating speed of the phonograph.

The phonograph is stopped and started by the single control means M. This consists of a shaft 142 extending between the frame plates adjacent the horn H. The outer end of the shaft is bent to form the handle M, and the rotation of the handle may, if desired, be limited by an appropriate stop 144. The shaft 142 carries a cam 146 which, in effect, acts as two cams. The outer periphery 148 of the cam is adapted to bear against and is so related to the top wall of the horn H that upon oscillation of the shaft, the cam tilts the horn about the bearing pins 86 in opposition to spring 98, and thus elevates the stylus from the record. Continued movement of the cam brings the leading edge 150 thereof into engagement with the upstanding finger 152 of the cam follower 96 and thus causes oscillation of the cam follower 96 and with it oscillation of the sound box. This movement is limited and the parts are locked in final position by a mating operation between the inner side or face wall of cam 146 and the straight edge 154 of the cam follower 96, and this final or limiting position determines the initial or starting position of the stylus N. The latter is in turn coincident with the first few sound grooves of the record, which are preferably left blank.

The control shaft 142 further carries at its rear end a small cam 160 which cooperates with a lever 162 pivoted at 164, as is best shown in Fig. 2, and carrying at its opposite end the governor brake shoe 140. The lever is held against the cam by a spring 166. Cam 160 is so designed that under normal playing conditions the brake shoe 140 is moved away from the governor to its normal governing position, whereas when the control shaft

142 is oscillated to elevate and restore the stylus to initial position the brake shoe is advanced against the governor and stops the phonograph.

It will thus be apparent that upon manipulation of the control M against the stop 144, three important operations are performed in proper sequential relation. The stylus is first elevated from the record and is only thereafter moved back toward its starting position. This prevents scratching of the record. The brake is applied after removal of the stylus, which in turn prevents a change in pitch or drooping of sound such as would result if the phonograph began to stop before the stylus were disengaged.

The phonograph mechanism need not be but 15 preferably is completely enclosed, and for this purpose the body of the frame may be closed by a thin sheet metal skirt or wall 170 the rear end of which is flanged at 172 to fit around the back frame plate 14, and the front end of which may 20 be secured to the front plate 12 by a tongue and slot relation 174. Similarly, the gear train T is preferably enclosed, and for this purpose a shallow dished sheet metal member 176 is placed over the gearing as a guard, it being secured to the 25 phonograph frame by a tongue and slot construction, or by screws as shown.

The front plate 12 is preferably made substantially larger than the rear plate 14, thereby providing an outwardly projecting flange 180 extending entirely around the phonograph, this flange being useful to limit the insertion of the phonograph in the doll body when mounting the same in place. The flange is perforated in any desired manner, dependent upon the particular kind of 35 doll body to which it is to be applied. The phonograph may, for example, be screwed to a metal doll body, or riveted to a rubber doll body, or sewed to a stuffed cloth doll body, and so on.

The operation of the phonograph should be apparent from the foregoing detailed description, but may be briefly reviewed as follows. With the control M moved to the stopped position, the winding key K may be turned to wind the phonograph. A record is slipped through the sound 40 discharge opening O onto the drum D. The phonograph is then ready to be played, and at any desired time the control M may be turned, thereby releasing the governor brake and permitting the stylus to be moved into engagement 45 with the record by the spring 98. The stylus is carried along the record by the sound groove itself and is moved freely because the sound box is freely pivoted on the horn H. The vibrations imparted to the stylus are translated into sound by 50 the sound box and are thence transferred through and amplified by the horn H, the channel section C, and the record drum D. At the end of the record it is simply necessary to turn the control M, whereupon the stylus is disengaged and moved 55 back to initial position, and the phonograph is stopped.

My miniature phonograph is characterized by numerous advantages among which I may list its compactness, for, as is evident from an inspection 65 of Fig. 2, for example, the phonograph is no larger than is needed for the record drum, the sound box, and the main drive spring, that is, the amplifier and usually bulky horn of the phonograph is so disposed that the phonograph structure is not appreciably increased in bulk. At the same time the horn is long and is characterized by continuous expansion, so that good amplification and clear reproduction are obtained. Only a single opening need be provided in the doll, this taking 75

care of both sound discharge and record change. Furthermore, the winding and starting control of the phonograph are localized at the same part of the doll. A single control fulfills all necessary functions for placing of the stylus as well as starting of the phonograph. The parts of the phonograph are simple and may be made with comparative cheapness, they being largely sheet metal. The main gear train consists simply of 5 spur gearing. While worm gearing is employed for the governor, this gear takes no substantial load and may be of inexpensive construction. The phonograph may be placed in relatively small dolls and is useful in a 12-inch doll, for example. 10 This is largely so because the phonograph may be arranged in an upright position, that is, longitudinally of the body of the doll.

It will be apparent that while I have shown and described my invention in preferred form, many 15 changes and modifications may be made in the structure disclosed without departing from the spirit of the invention defined in the following claims.

I claim:

25 1. A miniature phonograph comprising front and back plates, a hollow open-ended record rotating drum disposed between said plates near one end thereof, a main spring disposed between said plates near the other end thereof, gearing interconnecting the main spring and record drum, a sound box disposed between said plates at one side of the main spring, and a relatively long horn so disposed as not to appreciably increase the bulk 30 of the phonograph, said horn including a first horn chamber extending rearwardly from the sound box to the rear plate of the phonograph, a second horn chamber extending along the rear plate of the phonograph to the drum at the opposite end thereof, and a third horn chamber 35 formed by the drum, and a single large opening in the front plate at the drum for sound discharge and for changing the record on the drum.

40 2. A miniature phonograph comprising front and back walls, a hollow open-ended record rotating drum disposed between said walls near one end thereof, a main spring disposed between said walls near the other end thereof, a step-up spur gear train interconnecting the main spring and record drum, a sound box disposed between said plates at one side of the main spring, and a relatively long horn so disposed as not to appreciably increase the bulk 45 of the phonograph, said horn including a first horn chamber extending rearwardly from the sound box, a second horn chamber extending along the rear of the phonograph to the drum at the opposite end thereof, and a third horn chamber formed by the drum, a winding key at the front wall, and a single large 50 opening in the front wall for sound discharge and for changing the record on the drum.

55 3. A miniature phonograph comprising front and back plates connected by spacers, a hollow open-ended record rotating drum disposed between said plates near one end thereof, a main spring disposed between said plates near the other end thereof, a step-up spur gear train interconnecting the main spring and record drum, a sound box between said plates at one side of the main 60 spring, governor mechanism at the opposite side of the main spring, and a relatively long horn so disposed as not to appreciably increase the bulk of the phonograph, said horn including a first horn chamber extending rearwardly from the 65 sound box to the rear plate of the phonograph, a

second horn chamber extending along the rear plate of the phonograph to the drum at the opposite end thereof, and a third horn chamber provided by the hollow record drum, a winding key at the front plate, a control arm also located on the front plate for controlling the operation of the phonograph mechanism, and a single large opening in the front plate for sound discharge and for changing the record on the drum. 70

4. In a miniature phonograph, a frame having spaced stationary supports, a sound box between said supports, a sound box supporting horn extending across said sound box from one to the other of said spaced supports, said sound box being oscillatable on the sound box supporting horn, and said sound box supporting horn being oscillatably mounted on said spaced supports. 75

5. In a miniature phonograph, a frame including front and back plates, a sound box between said plates, a sound box supporting horn extending across said sound box between said plates, said sound box being oscillatable about its center on the sound box supporting horn, and said sound box supporting horn being oscillatably mounted on said frame, said sound box and sound box supporting horn having mating annular flanges for sound flow therebetween. 80

6. In a miniature phonograph, a frame, a sound box, a sound box supporting horn extending across said sound box in said frame, said sound box being oscillatable on the sound box supporting horn, and said sound box supporting horn being oscillatably mounted on said frame, said sound box and sound box supporting horn having hub supporting spiders with a pivot pin extending therethrough and acting as a bearing for oscillation of the sound box on the sound box supporting horn. 85

7. In a miniature phonograph, a frame including front and back plates, a generally circular sound box between said plates, a sound box supporting horn extending across said sound box between said plates, said sound box being oscillatable about its center on the sound box supporting horn, and said sound box supporting horn being oscillatably mounted on the frame, said sound box and sound box supporting horn having mating annular flanges for sound flow therebetween and further having hub supporting spiders with a pivot pin extending therethrough and acting as a bearing for oscillation of the sound box on the sound box supporting horn, one end of said sound box supporting horn leading to a second horn chamber. 90

8. In a miniature phonograph, a frame, a sound box, a sound box supporting horn extending across said sound box, said sound box being oscillatable on the sound box supporting horn, and said sound box supporting horn being oscillatably mounted on said frame, said sound box and sound box supporting horn having mating means acting as a bearing for oscillation of the sound box on the sound box supporting horn, said means extending through the sound box supporting horn and being provided with means for oscillating the sound box, one end of said sound box supporting horn leading into a second horn chamber. 95

9. In a miniature phonograph, a frame, a record rotating support, a sound box, a stylus thereon, a sound box supporting horn extending across said sound box, said sound box being oscillatable on the sound box supporting horn, and said sound box supporting horn being oscillatably mounted on the frame, and a control device to oscillate 75

the sound box supporting horn in order to bring the stylus into or out of engagement with a sound record, and means to oscillate the sound box on the sound box supporting horn in order to move the stylus from its terminal to its starting position.

10. In a miniature phonograph, a frame, a record rotating support, a stylus thereon, a sound box supporting horn extending across said sound box, said sound box being oscillatable on the sound box supporting horn, and said sound box supporting horn being oscillatably mounted on the frame, a bearing pin on the sound box extending through the sound box supporting horn and provided with means for oscillating the sound box, a control device having means to oscillate the sound box supporting horn in order to bring the stylus into or out of engagement with a sound record, and means to oscillate the sound box on the sound box supporting horn in order to move the stylus from its terminal to its starting position.

11. In a miniature phonograph, a frame, a record rotating support therein, a motor for driving said support, a governor for controlling the speed of the motor, a sound box, a stylus thereon, a sound box supporting horn extending across said sound box, said sound box being oscillatable on the sound box supporting horn, and said sound box supporting horn being oscillatably mounted on the frame, and a single control device having means to oscillate the sound box supporting horn in order to bring the stylus into or out of engagement with a sound record, and means to oscillate the sound box on the sound box supporting horn in order to move the stylus from its terminal to its starting position, and means for braking the governor in order to stop the motor.

40. 12. In a miniature phonograph, a frame including front and back plates, a record rotating support, a governor, a generally circular sound box between said plates, a stylus thereon, a sound box supporting horn extending across said sound box between said plates, said sound box being oscillatable about its center on the sound box supporting horn, and said sound box supporting horn being oscillatably mounted on the frame, said sound box and sound box supporting horn having mating annular flanges for sound flow therebetween and further having hub supporting spiders with a pivot pin extending therethrough and acting as a bearing for oscillation of the sound box on the sound box supporting horn, the aforesaid bearing pin on the sound box extending through the sound box supporting horn and being provided with cam follower means for oscillating the sound box, a single control device adjacent the sound box supporting horn having camming 50 means thereon adapted to oscillate the sound box

supporting horn in order to bring the stylus into or out of engagement with a record, and camming means to oscillate the sound box on the sound box supporting horn in order to move the stylus from its terminal to its starting position, and camming means for braking the governor.

13. In a miniature phonograph, a frame including front and back plates, a hollow open-ended record rotating drum therebetween, driving means therefor, a sound box between said plates, a stylus thereon, a sound box supporting horn extending across said sound box between said plates, said sound box being oscillatable on the sound box supporting horn, and said sound box supporting horn being oscillatably mounted on the frame, one end of said sound box supporting horn leading to a second horn chamber extending along the back plate to the drum, the drum acting as another horn chamber, a control having means to oscillate the sound box supporting horn in order to bring the stylus into or out of engagement with a sound record, and means to oscillate the sound box on the sound box supporting horn in order to move the stylus from its terminal to its starting position.

14. A miniature phonograph comprising a hollow open-ended rotatable record supporting drum, a reproducer and stylus mechanism for cooperation with a record on said drum, and sound chamber means extending from the reproducer to one end of the drum, the drum at said end being provided with a small diameter hub and spokes connecting the same to the shell of the drum, a driving shaft extending from the hub away from the drum and through the sound chamber means and serving to support the drum, the other end of the drum being unsupported and free to axially receive a cylindrical record, said drum acting as a sound amplifying chamber or horn for the phonograph.

15. A miniature phonograph comprising a generally closed casing, a hollow open-ended record rotating drum, a spoked hub at the rear end of the drum, a shaft connected to said hub to support and to drive the drum, the front end of the drum being unsupported and free to axially receive a cylindrical record, a sound box, and a horn so disposed as not to appreciably increase the bulk of the phonograph, said horn including a first horn chamber extending rearwardly from the sound box, a second horn chamber extending along the rear of the phonograph and opening into the rear end of the drum, and a third horn chamber formed by the drum, a single large opening in the phonograph casing at the forward end of the drum for sound discharge and for changing the record on the drum, the aforesaid shaft passing through and being supported by the second sound chamber.

JOHN H. WILHELM. 60
